(57) **CLAIM**

The ornamental design for a pistol charging handle, as shown and described.

DESCRIPTION

FIG. 1 is a perspective view of the pistol charging handle of the present invention.

FIG. 2 is a top side view thereof.

FIG. 3 is a bottom side view thereof.

FIG. 4 is a front elevation view thereof.

FIG. 5 is a rear elevation view thereof; and,

FIG. 6 is a first end view thereof, a second end being a mirror image of the first end view.

The pistol charging handle portions shown in broken lines form no part of the claimed design.
